UNITED STATES PATENT OFFICE.

ARMAND JACQUELIN, OF PARIS, FRANCE.

OSCILLATING SIEVE.

Application filed December 28, 1921. Serial No. 525,436.

To all whom it may concern:

Be it known that I, ARMAND JACQUELIN, citizen of the Republic of France, residing at 11 Avenue Pasteur, Paris, France, have 5 invented certain new and useful Improvement in Oscillating Sieves, of which the following is a specification, reference being had therein to the accompanying drawing.

My invention has for its object an oscillating sieve, provided with a series of special devices which are adapted to solve the problem of industrial sifting under particularly satisfactory technical and economical conditions.

10 The sieve forming the subject matter of this invention, comprises a casing mounted on a single horizontal shaft, located below the casing in front of the perforated surfaces of the riddles. The movement of the 20 sieve from back to front is the movement of progression of the products over the riddles of the sieve. The rear portion of the riddles is inclined towards the rear of the sieve, that is, towards that portion of the 25 sieve where the raw products are admitted to the sieve.

This particular inclination of the riddles results in the duration of the stay of the products on the rear portion of the riddles 30 being prolonged, which is advantageous for the reason that the rear portions of the riddles support the thickest layers of the product, and therefore, must be submitted to a prolonged and accelerated shaking.

35 In Figure 1 of the accompanying drawings there is shown diagrammatically an example of the arrangement of the sieve. A, B represents the perforated surface of a riddle of the sieve of which O is the horizontal shaft of oscillation. The foot H of the perpendicular dropped from O on the plane A, B is outside A of the perforated surface A, B and on the front side of the riddle.

40 The line C, F, represents the speed with which a body C, placed on the riddle A, B, is projected by the movement of oscillation in a direction at right angles to the radius of oscillation O, C, and is of a magnitude proportional to this radius. When 45 the body is moved from B towards A, that is to say from the rear to the front of the riddle, the speed of projection of this body therefore diminishes gradually and the same 50 is true of the horizontal component of this speed. For these two radii, the effects of

which are added together, the vertical component of the movement of projection of the grain deposited on the riddles A, B decreases very rapidly in proportion to 55 the progression of these grains forward.

On the other hand, the diagrammatic Figure 2, in which two riddles A, B and A', B' are shown, shows that two grains C and C', respectively placed towards the middle 60 of the riddle A, B and A', B' and on the same radius O, C, C', will have speeds of projection C, F, and C', F', having the same direction, but of different magnitudes, since they are proportional to the respective distances O, H and O', H' from the axis of oscillation O to the two riddles. We may 65 therefore say that in the arrangement shown, the mean amplitude of the bounds with which the material progresses over 70 any one of the riddles, is smaller the nearer the riddle considered is to the axis of oscillation, that is to say with smaller and 75 more numerous perforations.

The invention also relates to a system for 80 damping the oscillations of the sieve above described and to different constructional forms of this sieve.

Various arrangements according to the invention are represented by way of example 85 in the accompanying drawings in which:

Figure 3 is a general longitudinal section of the installation of the sieve.

Figure 4 is a transverse section on the line 4—4 of Figure 3.

Figure 5 is a side view of the sieve.

Figure 6 is a plane view of the whole of the installation.

Figure 7 is a longitudinal section through a vertical plane of a sieve according to the 95 preceding one and also shows curved riddles.

Figure 8 is a diagram explaining the working of these curved riddles.

Figure 9 is a longitudinal section through 100 a vertical plane of a sieve with curved riddles, certain of these latter dipping into cleaning water.

Figure 10 is an elevation of a sieve which permits the riddles to be cleaned during the 105 progress of the work.

The sieve comprises a parallelepipedal casing 1 resting on a single shaft of oscillation 2 by means of two triangular feet 3.

The walls of the casing carry perforated 110 sheet metal plates 4, 5, 6, 7, 8, 9, etc., which may be flat or curved, horizontal or inclined,

superposed over each other, and the front edges 14, 15, 16, 17, 18, 19, etc., of which are staggered relatively to each other as is shown in Figure 3, so that the waste from a grain which has just been broken up in the vicinity of these edges falls on to the perforated parts of the next riddle and are shifted there.

The single shaft of oscillation is placed 10 in the vertical plane of the next edge 19 of the bottom sheet or slightly in front of this plane.

The topmost perforated metal sheet is continued towards the rear by a solid sheet 15 20 suitably inclined towards the rear. The raw products are admitted over this plate. The inclination of this plate 20 is selected in such a way as to regulate in the best possible manner the delivery on to the sieve, 20 when the charging is intermittent. If the raw products contain a large proportion of dust which has to be previously separated, the charging plate 20 is replaced over a portion of its length by a special grid 21, 25 indicated by dotted lines in Figure 3 and which effects a preliminary elimination of the major portion of the dust. In order to carry out this removal of the dust, if this is necessary, a second special grid 22 is placed at the tail of the apparatus that is to say at the end of the bottom perforated sheet which is thus shortened by the length of this grid 22.

All the perforated metal sheets are extended towards the front by plates 24, 25, 26, 27, 28, 29, etc., which are not perforated in cases where the classified products require to be more or less diverted for the purpose of loading them up after sifting.

40 The fine products having passed through the bottom perforated metal sheet and if necessary, the special grid 22, are discharged outwards at the side through an inclined chute 30, and in cases where the sieve is combined with a dust removing grid at the front the dust eliminated by this grid can be returned to the chute 30 by a curved chute 31 placed at the back of the casing 1.

Finally in order to increase the time during 50 which the products to be drifted remain at the rear of the perforated metal sheets and consequently to improve the classification angle irons 34, 35, 36, 37, 38, 39, etc., staggered relatively to each other, are riveted to the perforated metal sheets in the rear portion of the casing.

In the modification shown in Figure 7, the sieve is provided with riddles 4, 5, 6, 7, 8, 9, etc., which affect the form of an arc-shaped surface inclined horizontally towards the rear of the sieve the geometrical axes of which are at right angles to the plane of oscillation of the sieve.

The inclination of this surface relatively 65 to the horizontal plane increases regularly

from front to rear of the riddle in proportion as the distance from this shaft of oscillation is increased.

This particular form given to the riddle has the effect of causing the products lying 70 on any one of the riddles to move forwards and upwards, and of slowing down their speed of progression in a measure which depends both on a fixed point M, (see Figure 75 8) and for a given frequency of oscillation, 75 on the horizontal inclination of the riddle and on the radius of oscillation (r). The profile of the curvature will be so chosen as 80 to produce on these riddles instantaneous speeds of progression which are best suited to the result which it is desired to obtain. In particular the length of time during 85 which the products to be sifted are stirred up on the rear zone of the riddles may be prolonged and consequently the efficiency of the sieve and the quality of the sifting increased.

The above sieve may be combined with unperforated charging plates 20 or these plates may be provided with the special grid 21 90 and suitably inclined (see Figure 7).

The advantage of considerably reducing the difference in height between the charging of the sieve and the mean level of outlet of the sifted products is thus obtained. 95

With the sieve with curved riddles the cleaning of the sieve in stagnant water may be effected. For this purpose, it suffices to cause the rear part of the cleaning riddle or riddles 70 (see Figure 9) to dip into the 100 water contained in a tank 71. The raw products are fed in through a hopper 72 and ascend up the inclined surface of the riddle 70 as shown by the arrow 73. The sifting of the cleaned products is then carried out in the sieve as before.

Any one of the modifications of the sieve according to the present invention may be combined with a series of special grids such as 22 placed in continuation of each metal 110 perforated sheet at the front of the sieve.

This arrangement permits of the double classification in diameters and thicknesses being obtained, each category of sifting on perforated metal sheets being freed 115 from flat products by the corresponding special grid.

It is advantageous to carry out this double classification prior to washing because it allows of the washing together of 120 products having practically not only the same diameter but also those of the same thickness.

Any one of the modifications of the sieve according to the present invention can be 125 provided with an arrangement which enables the riddles to be cleaned during the working of the sifting machine.

This arrangement consists of two openings 130 87 (see Figure 10) made in the side

walls 88 of the casing of the sieve over the whole height of the casing and affording ready access to the upper and lower faces of each riddle. The foreign bodies, 5 such as rags, paper and fragments of wood, are removed with a small rake or a hook. Any grains which might obstruct the perforations of the riddles are advantageously dislodged by giving a slight blow underneath the riddle by the aid of a small wooden board for example. As the operation of cleaning takes place during the working of the machine, the delivery outside the sieve of the grains thus dislodged 10 will take place in proportion to the cleaning operation.

The present invention also extends to a system for damping the oscillations of the sieve applicable to any of the forms of 20 sieve hereinbefore described.

One form of construction of this system for damping is represented in Figures 1 to 6.

An oscillating movement of small amplitude but of high frequency, is communicated to the casing by any suitable means 25 for example, by a connected rod 48 (see Figure 3) driven by a crank or eccentric. The driving shaft 41 itself receives a uniform rotary movement either by mechanical means or by hand, or finally as is shown in Figure 3 by a special motor 43 installed on the frame of the portable sieve.

The effects of the inertia developed by the 30 oscillating movement are damped by a damping system. This system is constituted by two groups of coiled springs, placed at the sides or at the rear of the sieve and symmetrically with respect to the plane of the longitudinal axis of this sieve. Each group comprises two series of springs 44, 45 which are placed on either side of a 35 fixed support 46 and are compressed alternatively during the periods of descent and ascent of the sieve. The springs 45, are opposed directly to an equal number of springs 44 and each one has its movable fulcrum on a small plate 47 mounted with adjusted nuts on the end of the rod 48 secured at 40 to the casing and consequently 40 oscillating with it. The fixed base of support common to all the springs, is constituted by a plate 46, fixed to the frame and cut away as at 49, for facilitating the 45 mounting and dismounting of the rods 48.

Circular plates 50, riveted to the fixed base and the movable base of each spring and having for diameter the internal diameter of the springs, hold these latter in place. 50 The plane of the movable base of the spring 44 passes advantageously in the immediate vicinity of the axis of oscillation 2, in order to reduce the lateral deformation of the springs as much as possible.

55 The resultant of the reactions of the

springs on the sieve passes advantageously in the vicinity of the centre of gyration of the sieve, so as to reduce to a minimum the fatigues of flexion of the oscillating casing.

The new arrangements above described 70 ensure the following industrial results as far as the shifting is concerned:

A.—A notable increase in the efficiency of the delivery that is to say of the tonnage per hour of raw material sifted, regard being had to the weight and dimensions of space occupied by the apparatus, and a notable improvement in the quality of the 75 calibration.

These two results are attained simultaneously:

1. By the possibility of producing an oscillating movement of high frequency by means of the use of the rational damping arrangement, which transmits elastically to 80 the frame of the apparatus almost the whole of the efforts of inertia which the driving members of the sieve would normally have to support, which they could only do to the great detriment of their good 85 state of preservation.

2. By producing the advance of the products over the classifying riddles in the form of bonds in height, of the same frequency as that of the movement of oscillation, but of variable form and magnitude suited on the one hand to the thickness of the layer of these products and on the other hand to the mean diameter of the grains of 90 the various categories of classification.

The advance by successive bounds results from the existence at all points of the 95 perforated metal sheets of a vertical component in the movement of oscillation and consequently in the movement of projection 100 of the grains.

The fact that the form and the amplitude of these bonds vary from one point to another, in a direction favourable to the qualities of classification, results from the special 105 arrangement of the single axis of oscillation placed as is described above. In actual fact on the one hand, as has been stated above, the vertical component of the movement of projection of the grains diminished rapidly 110 from the rear to the front of any riddle of the sieve. The rear zone of each riddle will therefore be quite specially a cleaning zone of accelerated sifting, particularly suited to the relatively thick layers of material which 115 are deposited there. On the other side each riddle will in this way be fed by the preceding one from the entry to the sieve and its surface will only be better utilized. Finally the cleaning thus effected has also 120 the effect of freeing the grains from the friable parts and the adhering dust. The angles 34, 35, 36, 37, 38, etc., which hold back the products for a longer time in the rear zone of the riddles, without constitut- 125 130

ing an obstacle of a permanent kind to the advance of these products, have the effect of prolonging the period of cleaning, the same effect being obtained with the arrangement of curved riddles (Figure 7).

On the other hand as has also been stated above the mean amplitude of the bounds by which the material progresses over any riddle is the smaller the lower the said 10 riddle is placed in the series, that is to say the perforations are smaller and consequently closer together from axis to axis. This result is obviously favourable to the better utilization of all the perforations.

15 B.—The possibility of obtaining a more complete classification.

This advantage results from the arrangements employed which permit of a large delivery of well calibrated products being obtained with an apparatus of moderate dimensions. Without appreciably augmenting either the weight and the amount of space occupied in height, it is possible to multiply more easily than in the other sieves 20 the number of perforated superposed metal sheets, the more so as the danger of obstruction being removed, the interval separating the successive metal sheets may be reduced with advantage.

30 C.—The arrangements forming the subject matter of the present invention permit of the expenses of upkeep and the consumption of motive power being considerably reduced.

35 This result is the direct consequence of the use of a rational damping group which reduces to insignificant values both the driving force and the fatigue of the driving parts.

40 D.—Portable sifting apparatus provided with a motor of the kind shown in the accompanying drawing and capable of a large output compared with its small weight and amount of room occupied, may be constructed.

45 E.—Finally a very satisfactory removal of the dust is obtained whatever the proportion of dust contained in the raw materials may be, by combining the new sieve with one or more special grids.

I claim as my invention:

50 1. In an oscillating sieve, the combination with a fixed support, of a casing, a single horizontal shaft carrying said casing, and arranged below the same in front of the perforated surfaces of the riddles of said sieve, the movement of the sieve from back to front being the movement of progression of the material over the riddles, the rear portion 55 of the riddles being inclined towards the rear of the sieve, i. e., towards that portion where the material to be treated is admitted to the sieve, and a damping system being interposed between the said casing and the said fixed support.

2. In an oscillating sieve, the combination with a fixed support, of a casing, a single horizontal shaft carrying the said casing, and arranged below the same in front of the perforated surfaces of the riddles of the 60 sieve, the movement of the casing from back to front being the progressive movement of the material over the said riddles, the rear portion of the riddles being inclined towards the rear of the sieve, i. e., towards the said portion where the material to be treated is admitted to the sieve, fixed angles in the rear portion of the sieve extending over the upper surfaces of the riddles perpendicular 65 relative to the path of progressive material over the riddles, and a damping system interposed between the said casing and the said fixed support.

3. In an oscillating sieve, the combination with a fixed support, of a casing, a single horizontal shaft carrying the said casing, and arranged below the same in front of the perforated surfaces of the riddles of the 70 casing, the movement of the sieve from back to front being the movement of progression of the material over the riddles, the rear portion of the riddles being inclined towards the rear of the sieve, i. e., towards that portion where the material to be treated is admitted to the sieve, a charging member for supplying the material to the sieve, said member forming an extension of the rear portion of the topmost riddle, and being also inclined towards the rear of the sieve, and a damping system interposed between the 75 said casing and the said fixed support.

4. In an oscillating sieve, the combination with a fixed support, of a casing, a single horizontal axis for carrying said casing and arranged below the same in front of the perforated surfaces of the riddles of the 80 said sieve, the movement of the sieve from back to front being the movement of progression of the material over the riddles, the rear portion of the riddles being inclined towards the rear of the sieve, i. e., towards that portion where the material to be treated is admitted to the sieve, a charging member for supplying the material to be treated to the sieve forming an extension of the rear portion of the topmost riddles, and being 85 also inclined towards the rear of the sieve, the water vessel adapted to receive the material to be treated, and arranged for the said charging member to dip into the said charging member, thus simultaneously causing the material to be treated to be cleaned and uniformly supplied to the topmost riddle of the sieve, and a damping system interposed between the said casing and the said fixed support.

5. In an oscillating sieve, the combination with a fixed support, of a casing, a single horizontal shaft carrying the said casing, and arranged below the same in front of the 90 said fixed support.

perforated surfaces of the riddles, the movement of the casing from back to front being the movement of progression of the material to be treated over the riddles, the rear portion of the riddles being inclined towards the rear of the sieve, i. e., towards that portion where the material to be treated is admitted to the sieve, a charging member for supplying the material to the sieve, a dust-

removing grid arranged on the said charging member, and a damping system interposed between the said casing and the said fixed support.

6. In an oscillating sieve, the combination with a fixed support, of a casing, a single horizontal shaft carrying the said casing, and arranged below the same in front of the perforated surfaces of the riddles of the said sieve, the movement of the sieve from back to front being the movement of progression over the riddles of the material to be treated, the rear portion of the riddles being inclined towards the rear of the sieve, i. e., towards that portion where the material to be treated is admitted to the sieve, dust-removing grids at the end of a certain number of riddles, and a damping system interposed between the said casing and the said fixed support.

7. In an oscillating sieve, the combination with a fixed support, of a casing, a single horizontal shaft carrying the said casing and arranged below the same in front of the perforated surfaces of the riddles of the said sieve, the movement of the sieve from back to front being the movement of progression over the riddles of the material to be treated, the rear portion of the riddles being inclined towards the rear of the sieve, i. e., towards that portion where the material to be treated is admitted to the sieve, the said casing having openings in its side walls, permitting ready access to the said riddles, and a damping system interposed between the said casing and the said fixed support.

45 8. In an oscillating sieve, the combination with a fixed support, of a casing, a single horizontal shaft carrying the said casing, and arranged below the same in front of the perforated surfaces of the riddles of the said casing, the movement from back to front being the movement of progression over the riddles of the material to be treated,

the rear portions of the riddles being inclined towards the rear of the sieve, i. e., towards that portion where the material to be treated is admitted to the sieve, and a damping system comprising two sets of springs interposed between the said casing, and the said fixed support, and acting in opposite direction to each other on the said casing.

9. In an oscillating sieve, the combination with a fixed support, of a casing, a single horizontal shaft carrying the said casing, and arranged below the same in front of the perforated surfaces of the riddles of the said sieve, the movement of the sieve from back to front being the movement of progression over the riddles of the material to be treated, the rear portion of the riddles being inclined towards the rear of the sieve, i. e., towards that portion where the material to be treated is admitted to the sieve, a damping system comprising two sets of springs, bearing with their ends on either side of a fixed support directly against said casing, and the other against a transverse plate connected to the casing.

10. In an oscillating sieve, the combination with a fixed support, of a casing, a single horizontal shaft carrying the said casing, and arranged below the same in front of the perforated surfaces of the riddles of the said casing, the movement of the sieve from back to front being the movement of progression over the riddles of the material to be treated, the rear portion of the riddles being inclined towards the rear portion of the sieve, i. e., towards that portion where the material to be treated is admitted to the sieve, a damping system comprising two sets of springs, the said springs bearing at their one ends against the said fixed support, and with the other end against the transverse plate connected with the said casing and a threaded stamp, and a nut for regulating the position of the said transverse plate relative to the said casing.

In testimony whereof I hereunto affix my signature in the presence of two witnesses. 100
